Primary Examiner — Mary Ann Calabrese(57) **CLAIM**

The ornamental design for a combined yard table and end support, as shown and described.

DESCRIPTION

FIG. 1 is a front view of a combined yard table and end support showing my new design, a rear view being a mirror image thereof;

FIG. 2 is a left side view of the combined yard table and end support;

FIG. 3 is a right side view of the combined yard table and end support;

FIG. 4 is a top view of the combined yard table and end support;

FIG. 5 is a bottom view of the combined yard table and end support;

FIG. 6 is a top front side perspective view of the combined yard table and end support; and,

FIG. 7 is a top front side perspective view of the combined yard table and end support shown in its assembled configuration.
